UNITED STATES PATENT OFFICE.

ERNEST F. SIBELL, OF CHICAGO, ILLINOIS.

COLLAR.

1,127,297.

Specification of Letters Patent.

Patented Feb. 2, 1915.

Application filed April 19, 1913. Serial No. 762,313.

To all whom it may concern:

Be it known that I, ERNEST F. SIBELL, citizen of the United States, residing at Chicago, in the county of Cook and State 5 of Illinois, have invented certain new and useful Improvements in Collars, of which the following is a specification.

My invention relates to collars of the type known as turn-over or turn-down collars involving the usual inner and outer bands 10 formed from the same piece of material.

The primary object of the invention contemplates the provision of a turn-over collar wherein the tie or cravat is held in 15 proper place by means of two spaced apart strips arranged between the collar bands, one near each end or extremity of the collar.

A further object of the invention is to provide means for retaining the tie in 20 proper place with respect to the collar flaps or ends, thus preventing the falling of the tie or bow below the meeting ends of the collar, and at the same time insuring a neat and attractive fastening for both the collar 25 and the tie.

A still further object of the invention resides in the provision of means including a reinforcing strip adapted to be secured to the collar extremities for effectually supporting the collar flaps in proper place, and 30 under certain conditions preventing the collar from wilting at the meeting end thereof.

The above and additional objects are accomplished by such means as are illustrated in their preferred embodiment in the accompanying drawings, described in the following specification and then more particularly pointed out in the claims which are 35 appended hereto and form a part of this application.

In describing my invention in detail reference will be had to the accompanying drawings wherein like characters denote like 45 or corresponding parts throughout the several views, and in which:

Figure 1 is a front elevation of the collar constructed in accordance with my invention; Fig. 2 is a rear elevation; Fig. 3 is 50 a section on the line 3—3 of Fig. 2; and Fig. 4 is an elevation partly broken away, illustrating the manner in which the tie is fastened to the collar.

Proceeding now to the description of the 55 drawings, wherein is illustrated the pre-

ferred form of my invention, the numeral 1 designates the outer band of the collar, and 2 the inner band, the latter being somewhat longer than the band 1 for the purpose of creating flaps 3 of any of the well known 60 shapes. The said two bands, 1 and 2 are preferably composed of a single piece of material bent as at 4 for the purpose of creating the two collar sections or bands, the lower edge of the said two bands being 65 stitched or otherwise sewed as at 5 throughout the greater portion of the length thereof. The lower edges of the two bands are stitched together to a point 6, the said point 6 being in spaced relation to the extremities 70 of the bands 1 and 2 so as to form the flaps 3 from a continuation of the said band 2.

To reinforce the flaps 3, a strip 7 is provided, the said strip being stitched to the said band 2 throughout its upper edge and 75 extending as at 8 in a curved line to the point 6, thereby supporting the said flaps 3 through their entire length, thus preventing wilting of the collar at this particular point. The usual button holes 9 are formed within 80 the flaps 3 for the purpose of fastening the collar over the ordinary collar button (not shown).

A rear collar button hole 10 is formed within a strip 11 sewed upon the inner face 85 of the band 2 as at 12, this construction permitting the desired fastening of the collar at the rear thereof without allowing the collar button to contact with the tie or cravat or in any way interfere with the sliding of 90 the latter between the passageway formed by the provision of the said two bands 1 and 2 should the tie be arranged in the usual manner.

To effect a secure connection between the 95 flaps 3 when the collar is buttoned or fastened at the front, strips 13 are provided, one upon the inner face of each flap 3, and disposed between the said flap and the outer band 1 near the extremities of the latter. 100 After buttoning or fastening the collar in the usual manner, the overlapping flap is adapted to be passed between the said strip 13 and the opposite or adjacent flap, thereby fastening one of the said flaps in proper 105 place with respect to the other or opposite flap.

After fastening the collar flaps or extremities as above set forth with the overlapping flap beneath one of the retaining 110

strips 13, the cravat or tie is passed through or over the said strips so as to additionally fasten the collar ends together. By tying the cravat, the strips may be drawn together 5 for effecting a close meeting front to the collar and insuring a neat and attractive appearance at all times. The cravat when secured to the retaining strips is tied in the usual manner so as to depend from the collar front as desired.

It will be seen from the above, taken in connection with the accompanying drawings that a dropping of the cravat or tie 10 from between the overlapping or meeting ends of the collar is prevented by the effective support created by the provision of the said retaining strip; that the said strips will permit the overlapping ends of the collar to be adjusted according to the desire 15 and taste of the wearer; that the reinforcing strip 7 will additionally support the flaps at the points that would otherwise be weakened were the said strips not provided; and that the bands 1 and 2 of the collar, between the 20 flaps 3 thereof may be starched together when the collar is laundered as it is unnecessary when applying the cravat to pass the same between the said two bands.

It will be understood that the above description and accompanying drawings comprehend only the general and preferred embodiment of my invention and that various minor changes in the details of construction, proportion and arrangement of parts 30 may be made within the scope of the appended claims and without sacrificing any of the advantages of my invention.

Having thus fully described my invention,

what I claim as new and desire to secure by Letters Patent, is:—

1. A turn-over collar including an inner and outer band, the lower edges of the said two bands being connected together throughout the greater portion of the length thereof, the inner band extending beyond the extremities of the said outer band to form flaps for the collar, reinforcing strips secured to the flaps, and means including a pair of retainer strips carried by the said flaps adapted to form a supporting means 40 for the cravat or tie, as and for the purpose set forth.

2. A turn-down collar including an inner and outer band the inner band extending beyond the extremities of the outer band to form flaps for the collar, the said two bands being connected at their lower edge throughout a greater portion of the length thereof, reinforcing strips secured to the outer face of the said flaps, a strip secured to the rear inner face of the inner band within which the rear button hole is formed, retaining strips secured upon the outer face of the flaps by means of which the cravat is retained in proper place, one of the said flaps 45 adapted to extend beneath one of the said strips when the collar is fastened, the said two strips adapted to be drawn toward each other for adjusting the position of the collar, as and for the purpose set forth.

In testimony whereof I affix my signature in presence of two witnesses.

ERNEST F. SIBELL.
